UNITED STATES PATENT OFFICE.

HENRY E. REEVE, OF BROOKLYN, NEW YORK.

GONG.

1,186,942.

Specification of Letters Patent. Patented June 13, 1916.

Application filed September 23, 1915. Serial No. 52,308.

To all whom it may concern:

Be it known that I, HENRY E. REEVE, a citizen of the United States of America, residing at 459 Carroll street, Brooklyn, New York, have invented new and useful Improvements in Gongs, of which the following is a specification.

This invention relates particularly to gongs of the single stroke type, the general objects of the invention being to simplify and improve gongs of this character and to produce a gong which will possess the added advantages of being relatively inexpensive in construction and free of complicated parts.

A special object is to protect the parts which might be injured by the action of the elements and to prevent access of dust, fumes and moisture to such parts.

A further object is to secure a powerful action of the hammer on the gong top or bell and to obtain this without undue current consumption.

Other objects and features of the invention will appear as the specification proceeds.

In the drawing accompanying this specification and wherein I have illustrated a practical and preferred embodiment of my invention, the actuating electro-magnet is mounted on a horizontal support and the driving connection from the armature of said magnet to the hammer is made by an arm or extension on the armature projecting down below the horizontal support and into position above a laterally extending arm on the hammer. This leaves the hammer free to swing into engagement with the bell or gong top so that the action of the armature is to throw the hammer forcibly into engagement with the bell. A flexible diaphragm is preferably provided at the point where the armature arm projects down through the horizontal support and a close fitting cover is preferably applied to the horizontal support, housing and protecting the electromagnet and its armature.

A further feature is the provision of a roller at the point of engagement between the armature arm and the hammer arm. This reduces friction and prevents the accumulation of foreign matter which might interfere with the stroke of the hammer.

Another feature of the invention is a special form of buffer spring for the hammer consisting of a piece of spring metal

anchored at one end and bent upon itself to provide a spring arm disposed in the path of the hammer and supported at the point of the bend therein.

The accompanying drawing while illustrating a concrete and practical form of the invention is not intended to limit the invention to this particular form, it being understood that various changes and modifications may be made without departing from the true spirit and scope of the invention.

Figure 1, is a side elevation with parts broken away and in section, of a single stroke gong constructed in accordance with and embodying the invention, the section being taken on a plane indicated by the line 1-1 in Fig. 2. Fig. 2, is a front view of the same, partly in section, the plane of the section being indicated by the line 2-2 in Fig. 1. Fig. 3 is a broken plan view of the conduit connection appearing at the left in Fig. 2: Fig. 4, is a diagrammatic view illustrating the increasing leverage exerted by the armature on the hammer.

In the illustration 7 designates the frame or body of the gong, of substantially triangular formation and carrying at its lower end a post 8 to which the bell or gong top 9 is secured by a screw 10. This frame carries at the top a substantially horizontal supporting shelf 11, this supporting shelf being secured on top of the upper ends of the side arms of the triangular frame by screws 12. This shelf or base plate is preferably made of sheet metal so that the openings necessary to be formed therein for screws, etc. may be produced by a simple punching action.

The electromagnet 15 is carried by an angular bracket 16 suitably secured in position on the supporting shelf as by means of the screws 17. This electromagnet is preferably of double pole construction as indicated in Fig. 1. The armature 18 of the electromagnet is pivotally supported on spindles 19 having a bearing in the sides of the U-shaped bracket 20. Both the electromagnet and the armature are preferably magnetically separated from the support on which they are mounted, this being accomplished in the present instance by the interposition of a layer of insulating material 21 between the magnet supporting bracket 16 and the base plate 11 and by the use of non-magnetic bearing bushings 22 for the armature spindles 19. The stroke of the ar-

mature may be limited by providing it with a pin or lug 23 engaging in a limiting opening 24 formed in one of the upstanding side arms of the armature supporting bracket 20.

5 The hammer 25 of the gong top is pivotally supported below the substantially horizontal supporting shelf on a pivot pin 26. A convenient and very practical mounting for the hammer is provided in the illustration by a substantially U-shaped channel member 27 secured to the under side of the supporting shelf by screws 28, the dependent side walls of this channel member serving as a support for the pivot pin of the hammer.

15 The operating connection from the armature to the hammer comprises a downwardly projecting arm or lever 30 carried by the armature and having a one-way driving engagement with an arm or lever 31 carried by the hammer. This one-way driving engagement is preferably provided by extending the hammer arm 31 laterally to one side of the pivotal support 26 and by extending 20 the armature arm 30 laterally into position above said hammer arm. This construction provides a very compact arrangement of parts, enabling the placing of the hammer directly beneath the electromagnet instead 25 of off to one side of the same. To reduce friction at the point of engagement between the arms there is preferably provided a friction reducing roller 32, this roller in the illustration being carried by the laterally extending arm of the hammer. The engaging surface of the armature arm is preferably inclined as indicated at 33 so as to lie in a plane coincident with the pivotal axis 30 of the armature, as indicated by the dotted line 34 in Fig. 4.

35 The electrical parts of the device are preferably protected against moisture, etc., by means of an air-tight and liquid proof flexible diaphragm closing the opening in the horizontal support through which the armature arm projects. This diaphragm is indicated at 35 and the same consists of a pair of flexible metallic disks connected together at their periphery, the upper one being secured to the armature by means of a central bushing 36 and the lower disk being secured to the support by the central bushing 37, this latter bushing having an opening 38 therethrough, through which the armature arm 30 projects. This flexible diaphragm in addition to its function as an air-tight and liquid-proof closure acts in the capacity of a spring, tending to force the armature toward the core heads of the magnet. In addition to this spring effect, a separate spring 69 may be provided tending to force the armature toward the magnet and so to partly overcome the weight of the hammer.

40 85 The stroke of the hammer is cushioned

and the hammer is started on its return stroke by means of a buffer spring. This spring as indicated in Fig. 2 preferably is in the form of a strip of spring metal anchored at one end at 40 and bent around a 70 stud or support 41 to provide the reversely directed spring arm 42 which is disposed in the path of movement of the hammer. The anchorage 40 for the buffer spring and the support 41 at the bent portion of the spring 75 are preferably in the form of pins as indicated in Fig. 2 engaged between the dependent side walls of the channel member 27.

It will be noted that the channel member in addition to serving as a support for the 80 hammer and the buffer spring serves also as a housing for these parts and for the armature arm which extends down into the chamber provided between the side walls of said member. The protective effect thus obtained may be further carried out by providing plates 43 engaged between the sides of 85 said channel member and closing in the space therebetween.

90 In the normal condition of rest the hammer swings down by gravity until it rests against the stop 45 provided on the upper side of the post which supports the bell as indicated in Fig. 2. When the magnet is energized, the armature is forcibly drawn toward the pole of the magnet and the armature arm swings downward, forcing the hammer arm downward and throwing the hammer upward into engagement with the 95 rim of the gong top. This sudden movement imparted to the armature swings the hammer with great force into engagement with the gong top. The stroke of the armature is limited so that it can carry the hammer only about to the position indicated at 100 the left in Fig. 2 in dotted lines, the hammer after being carried to this point continuing its movement into engagement with the gong top by reason of its momentum. The hammer is thus freed of the armature 105 before the time of contact with the gong top and therefore strikes the gong top a quick, sharp blow, rebounding freely after its contact therewith. This freedom of movement insures a quick return of the hammer and 110 prevents any interference between the gong top and hammer due to the vibration set up in these parts.

115 The blow of the hammer is further actuated by increasing the leverage exerted 120 on the hammer. This effect is illustrated in Fig. 4 wherein the line 47 illustrates the effective leverage exerted by the armature arm upon the hammer arm at the commencement of the stroke and the line 48 indicates 125 the effective leverage exerted at the end of the armature stroke. The hammer is thus given an accelerated movement resulting in a very forceful blow.

130 In the drawing I have illustrated a pre-

ferred method of connecting the gong in circuit, which consists in providing a terminal chamber at one side of the gong arranged to receive the sections of conduit. This 5 terminal chamber is made up in the present instance of a U-shaped chamber member having top and bottom walls 50 and 51 connected by an upright back wall 52, said member connecting with flanges 53, 54 on the gong and having an open side closed by a removable cover 55. This cover at one end hooks into engagement with a stud 56 and is secured at its opposite end by a screw 57. The sections of conduit 58 are engaged with 10 the top and bottom 50 and 51 on the chamber member and the service wires are connected with suitable terminals 59 and 60 carried by the gong within the chamber thus provided.

20 The magnet terminals 59 and 60 may conveniently be carried by the cover 65 which houses the electromagnet and its armature. This cover is secured in air-tight waterproof engagement with the substantially 25 horizontal base plates 11 by means of screws 66, a gasket 67 being interposed at the joint between these parts. This gasket may be extended inward as indicated in Fig. 2 to provide the insulating layer 21 between the 30 base plate and the magnet supporting bracket 16.

It will be noted that in the above described construction and arrangement of parts, the pivotal axis of the hammer, the 35 axis of the armature and the axis of the roller are all substantially parallel to a plane indicated by the line 70 taken through the axes of the cores of the electromagnet. This arrangement enables the application 40 of the greatest power to the hammer and enables the employment of a relatively small current to produce a comparatively powerful hammer-like blow. The magnetic insulation of the electromagnet and its armature 45 further conserves the power and thereby reduces the amount of current necessary.

From the foregoing it will be seen that my invention provides a gong which is extremely simple and practical in its construction, which is weather-proof and which is 50 quick and positive in its action.

What I claim is:—

1. In an electric gong, an electromagnet, a hammer pivotally supported beneath said 55 electromagnet and provided with a laterally extending arm, an armature for said electromagnet, an actuating arm connected with said armature extending laterally beneath the electromagnet and into position above the laterally extending arm of the hammer and a bell disposed in position to be engaged by said hammer.

2. An electric gong comprising a substantially horizontal shelf provided with an 60 opening therethrough, an electromagnet

mounted on top of said shelf and an armature for said electromagnet pivoted on said shelf, an arm connected with said armature projecting downwardly through the opening in the shelf and thence laterally beneath said shelf, a hammer pivotally supported below the shelf and provided with a laterally projecting arm disposed beneath the armature arm, a bell disposed in position to be engaged by said hammer and a 70 cover housing the electromagnet and the armature and detachably secured to said shelf whereby upon removal of said cover the electromagnet and armature may be wholly exposed.

3. In an electric gong, an electromagnet, a hammer pivotally supported beneath said electromagnet and provided with a laterally extending arm, an armature for said electromagnet, an actuating arm connected with said armature extending laterally beneath the electromagnet and into position above the laterally extending arm of the hammer, a friction reducing roller interposed between the armature arm and hammer arm, and a 80 bell mounted in position to be engaged by the hammer.

4. In an electric gong, a horizontally disposed electromagnet, an armature pivotally supported at the pole end of said electromagnet, a hammer pivotally supported below the electromagnet and having an actuating arm extending laterally into position beneath the electromagnet and an arm carried by the armature extending laterally 95 beneath the plane of the electromagnet into position above the hammer arm.

5. In an electric gong, a pivoted hammer, a gong top to be engaged thereby, a buffer spring anchored at one end and having a 100 reversely bent portion disposed in the path of movement of the hammer, a support engaging the buffer spring at the bend therein, an armature having a driving connection with the hammer and an electromagnet 110 for actuating said armature.

6. An electric gong comprising a substantially horizontal support, an electromagnet mounted on said support, an armature for said electromagnet mounted on the support, 115 spaced supporting walls dependent from the horizontal support, an arm carried by the armature projecting down below the horizontal support, a hammer pivotally supported between the dependent supporting walls provided with a laterally extending arm engaged by the armature arm and a bell engaged by said hammer.

7. In an electric gong, a substantially horizontal support, an electromagnet 120 mounted on said support, an armature for the electromagnet mounted on the support, a channel-member secured beneath the horizontal support, a dependent arm carried by the armature and projecting down below 130

- the horizontal support and into the channel-member, a hammer pivoted in the channel member and having a laterally extending arm inclosed in the channel member and engaged by the armature arm and a bell adapted to be engaged by the hammer.
8. In an electric gong, a substantially horizontal support, an electromagnet mounted on said support, an armature for the electromagnet mounted on the support, a channel member secured beneath the support, a dependent arm carried by the armature and projecting below the support, a hammer pivoted in the channel member and engaged by the armature arm to move said hammer toward the bell, a bell adapted to be engaged by the hammer and a buffer spring for the hammer supported by and inclosed within the channel member.
10. In an electric gong, a substantially horizontal support provided with an opening therethrough, an electromagnet mounted on said support, an armature for said electromagnet mounted on the support, an

arm carried by the armature and projecting down through the opening in the horizontal support and thence laterally below said horizontal support, a flexible dust-tight and liquid-proof diaphragm closing the opening in the horizontal support, a cover detachably secured to the horizontal support, and having a dust-tight and liquid-proof connection therewith, a hammer pivoted below the horizontal support operatively engaged by the laterally extending portion of the armature arm and a bell adapted to be engaged by said hammer.

10. In an electric gong, an electromagnet, a pivoted armature therefor, a housing incasing the electromagnet, a hammer pivotally supported having an actuating arm whose fulcrum is coincident with that of the hammer, an arm carried by said armature projecting through a wall of said housing and extending laterally beneath said wall into engagement with said hammer arm.

HENRY E. REEVE.
